UNITED STATES PATENT OFFICE.

WILLIAM F. DONATHAN, OF WINCHESTER, TENNESSEE, ASSIGNOR TO STEPHEN J. GRAHAM, OF TUCKERMAN, ARKANSAS.

FRAUD PREVENTER FOR COIN-CONTROLLED DEVICES.

Original application filed November 30, 1925, Serial No. 72,375. Divided and this application filed March 15, 1926. Serial No. 94,820.

This is a divisional application of my co-pending application filed November 30th, 1925, and bearing Serial Number 72,375.

The present invention relates to improvements in fraud prevention devices for coin controlled mechanisms.

One of the important objects of the present invention is to provide a simple and efficient means for testing a coin which is dropped into the machine prior to the coin reaching the coin controlled mechanism of the vending machine so that slugs and the like will be prevented from actuating the coin controlled mechanism.

Another important object is to provide a fraud preventing device of the above mentioned character which is adapted to receive and test coins of various denominations.

A still further object is to provide a fraud preventing device of the class described which will bend and mutilate slugs which are inserted in the machine so as to prevent such a check actuating the coin controlled mechanism of a vending machine, the mutilated slugs being thrown out of the machine.

A further object is to provide a fraud preventing device for coin controlled mechanisms, which is simple in construction, inexpensive, strong, and durable, and further well adapted to the purpose for which it is designed.

Other objects and advantages of the invention will become apparent during the course of the following description taken in connection with the accompanying drawings.

In the accompanying drawings forming a part of this application and in which like numerals designate like parts throughout the several views:

Figure 1 is a top plan view of the fraud preventing device embodying my invention showing the same arranged in the upper portion of a coin controlled vending machine,

Figure 2 is a vertical sectional view taken approximately on line 2-2 of Figure 1.

Figure 3 is a vertical section taken approximately on line 3-3 of Figure 2 with parts shown in elevation.

Figure 4 is a detail perspective view of the deflector plate forming a part of the present invention, and

Figure 5 is a diagrammatic view of the device.

55

For the purpose of illustrating the manner in which the fraud preventing device embodied in the present invention is associated with the coin controlled mechanism of a vending machine, I have shown in the drawings, such parts of the vending machine as are essential.

60

In the drawings, the numeral 4 designates the outer casing of a vending machine which is adapted for rotation about the stationary inner casing 19 in the manner which is more fully described in another divisional application covering the vending machine structure per se.

65

A cover 23 is disposed over the opening 18 formed in the central portion of the cover 17 which is provided for the top of the casing 4, and this cover 23 is supported in a stationary manner by means of the bracket 24, the lower ends of the latter being secured to the inner wall of the stationary casing 19. The central portion of the cover 23 is thickened and arranged therein are the vertical coin receiving slots 25, 26, and 27 respectively. The slot 25 is of such diameter as to be adapted to receive a five-cent piece; the slot 26 being adapted to receive a ten-cent piece, and the slot 27 a twenty-five cent piece. Suitable indicating means such as is shown at 28 is associated with each of the slots.

70

80

The construction of the fraud preventing device will now be specifically described.

Carried by the bottom of the cover 23 and extending downwardly into the upper portion of the stationary casing 19 are the coin chutes 29, 30, and 31 respectively. The upper ends of these coin chutes register with the bottom of the respective coin receiving slots, and these chutes are also of such width as to receive coins of a predetermined denomination.

85

A transversely extending relatively thick shaft 32 is journaled at its respective ends in the frame 33 and is adapted for rotation therein, this shaft being disposed directly below the lower ends of the respective coin chutes which depend from the bottom of the cover 23. The frame 33 is supported on the bracket 33', the latter being secured on the top of the coin controlled supporting blocks in the manner clearly shown in the

90

95

100

105

drawings. This shaft 32 has formed therein at predetermined places, the coin receiving pockets 34, 35 and 36 respectively. This is more clearly illustrated in Figure 1 of the drawings. These pockets cooperate with the lower ends of the coin chutes 29, 30, and 31 respectively in the manner presently to be apparent.

A series of spaced knurled rollers 37 are 10 mounted on the frame adjacent the shaft 32 in spaced relation thereto, and directly opposite the several coin receiving pockets which are formed in the shaft. As is shown more clearly in Figures 1 and 2, each roller 15 is journaled for rotation in the upper portion of the bracket 38, the lower end of which is pivotally supported at 39 in the frame. This will permit the swinging movement of each roller toward and away from 20 the shaft 32.

A curved flat spring 40 is secured at its lower end on the frame directly behind each bracket 38, the upper free end of each spring being in engagement with the upper rear portion of the respective bracket for normally forcing the knurled rollers toward the shaft 32. The set screws 41 which are threaded transversely through the supports 42 therefor at the rear longitudinal sides 25 of the frame 33 engage the respective spring elements 40 for adjusting the tension thereof.

A substantially rectangular plate 43 is 30 rigidly secured in a longitudinal cut out portion provided therefor in the shaft 44 and the latter is provided with suitable trunnions 45 at its respective ends. These trunnions are journaled in the respective ends of the frame 33 so that the rotatable shaft 40 44 is disposed longitudinally in the frame and below the aforementioned shaft 32 and slightly rearwardly thereof as is shown more clearly in Figure 2.

The shafts 32 and 44 are adapted for 45 simultaneous rotation through the medium of the intermeshing gears 46 and 47 respectively. An elongated hopper 48 is arranged below the shaft 44, and the rear side thereof is cut away as illustrated in Figures 2 and 5 of the drawings for cooperation with the deflector plate 43 which is secured on the shaft 44. Extending downwardly from the bottom of the hopper 48 and communicating therewith are the additional coin chutes 49, 50, and 51 respectively. These additional coin chutes are preferably arranged in alignment with the aforementioned coin receiving pockets which are formed in the rotatable shaft 32.

60 As is more clearly illustrated in Figure 3, the coin chutes 49, 50, and 51 are disposed directly below the coin chutes 29, 30, and 31 respectively. The lower ends of the coin chutes 49, 50, and 51 are slightly cut away to accommodate the various coin re-

ceiving discs forming a part of the coin controlled mechanism which in the present instance is designated generally by the numeral 52. The construction of the coin controlled mechanism has been more fully disclosed and described in my copending application bearing Serial Number 72,375.

The actuating means for the fraud preventing device comprises a vertical driven shaft 75, the upper end of which extends 70 upwardly through a substantially U-shaped bracket 76 which is arranged on the front side of the frame 33.

A relatively short shaft 89 is journaled for rotation between the arms of the U-shaped 80 bracket 76. A gear 90 is carried by the outer end of the shaft 89, and the same meshes with the gear 46 which is carried by the shaft 32. The shaft 89 is rotated through the medium of intermeshing bevelled gears 91 and 92 which are carried by the upper end of the shaft 75 and the intermediate portion of the transverse shaft 89 respectively. This construction is clearly 85 illustrated in Figures 1 and 3 of the drawings.

As the manner in which the shaft 75 is 90 operated, and also the manner in which the same actuates the coin controlled mechanism is fully covered in my aforementioned copending application bearing Serial No. 72,375, a further explanation thereof in this 95 application is thought unnecessary.

Adapted to be associated with the fraud preventing device is an additional hopper 140 146, the same being arranged at the rear side of the hopper 48 and adjacent the coin chutes 49, 50 and 51. Projecting upwardly from the front face of the additional hopper 146 is the lip 147, the same being adapted for 105 cooperation with the deflector plate 148 which is inclined downwardly from the rear side of the hopper 48. This construction is clearly illustrated in Figure 5 of the drawings.

A coin chute 149 extends from the bottom of the hopper 146, and this chute is disposed toward the front of the machine so that the discharge end thereof will communicate with the delivery chute (not shown in the present application but is clearly illustrated and described in my copending application).

The operation of the fraud preventing device may be briefly stated as follows. When the proper coin is deposited in one of the coin receiving slots provided in the cover 23, it will readily be seen that the coin will by gravity pass downwardly through the respective chute and will be discharged into the pocket provided therefor in the shaft 32, and which pocket is disposed in registry with the particular slot in the cover 23 in which the coin was initially inserted. The shaft 89 will be driven by the shaft 75 when the latter is actuated, and the shaft 32 will 125 130

therefore also be rotated. The shaft 44 will rotate simultaneous with the actuation of the aforementioned shaft, as is readily obvious from the construction shown in Figure 2. 5 As the shaft 32 rotates in the direction of the arrow, the coin will be moved into engagement with the spring pressed knurled roller 37 which is disposed adjacent the shaft 32 in which the pockets are formed. If the 10 proper coin has been inserted in the machine, the coin will pass the roller without being bent and will fall upon the plate 43 which will then be in a position shown in the full line in Figure 5 of the drawing, thus acting 15 as a guide for deflecting the coin into the hopper 48, from which the same passes through one of the chutes and is discharged into the coin controlled mechanism 52.

Should a slug or other fraudulent checks 20 be inserted in any one of the slots 25, 26, and 27, such a slug will enter one of the pockets formed in the shaft 32, depending upon the size of the slug inserted, and when the shaft 25 is actuated, to effect the rotation of the shaft 32, the slug will also move toward the knurled roller 37, and if the slug is of a soft 30 material, the spring pressed roller 37 will cooperate with the shaft 32 to effect the bending or mutilation of the slug in the manner as shown very clearly in Figure 5 of the drawings.

The spring pressed roller which bends the slug will be in engagement with the outer edge portion of the slug during the rotation 35 of the shaft 32 and the shaft on which the deflector plate 43 is secured, and during the bending operation, the rotation of said shaft will be retarded. By reason of the slug being bent, the same will therefore remain in one of the pockets in the shaft 32 for a longer period than would a proper coin and therefore by the time the pocket in the shaft 32 has reached the position which will permit the bent slug to fall out of the pocket by 40 gravity, the deflector plate 43 will have assumed the position shown in the dotted lines in Figure 5.

The plate 43 will then provide a closure 50 for the hopper 48 and when the bent or mutilated slug is discharged from the shaft 32, the same will fall upon the plate 43 and instead of being dropped into the hopper 48, the same will fall into the hopper 146 and will by gravity pass downwardly through the chute 149 and will be discharged out into the delivery chute (not shown), thus returning the slug to the person attempting to operate the machine and at the same time preventing any merchandise being discharged from the machine as well as preventing any possibility of the proper coins which are contained within the change holding magazines arranged in the machine being discharged with the packages.

60 In order to prevent slugs which are formed

of a relatively hard metal operating the coin controlled mechanism of a vending machine to effect a package therefrom, the frame 33 may be magnetized. As the shaft 32 rotates, it will carry with it in one of the pockets formed therein such a slug and when the slug or check reaches the magnetized portion of the frame, said coin will be automatically displaced from its pocket in the shaft 32 before the plate 43 has moved to the position 70 shown in the full lines, and will also cause such a slug to be returned or discharged to the person attempting to operate the machine. 75

80 A fraud preventing device of the above mentioned character may be associated with any type of a vending machine which employs a coin controlled operating mechanism. The present device will test the coins which will be deposited in the machines so that 85 slugs will be prevented from being used to operate the machine.

Furthermore, the provision of a slug handling mechanism of the above mentioned character will prevent any possibility of a 90 loss being sustained by the owner or operator of the vending machine.

The construction of the device will not in any way interfere with the actuation of the coin controlled mechanism when a proper 95 coin is inserted in the machine. The simplicity in which my improved device is constructed renders the same easily and readily assembled and will furthermore be inexpensive, yet strong and durable, and at all times 100 positive and efficient in carrying out the purposes for which it is designed.

While I have shown the preferred embodiment of my invention, it is to be understood that minor changes in the size, shape 105 and arrangement of parts may be resorted to without departing from the spirit of the invention or the scope of the appended claims.

Having thus described the invention, what I claim as new and desire to secure by Letters Patent is:—

1. A fraud preventing device comprising a rotatable shaft provided with a coin receiving pocket, a spring pressed roller supported adjacent the shaft and cooperating with the shaft to bend a slug placed in said pocket when the shaft is rotated, and a deflector operatively associated with said shaft and disposed below the shaft and said roller. 115

2. In combination with a coin controlled actuating mechanism, a fraud preventing device associated therewith comprising a coin receiving means, a spring pressed member cooperating with said coin receiving means to bend a slug inserted therein, and a deflector operatively associated with said shaft and disposed below the shaft and said roller for preventing the slug operating said coin controlled actuating mechanism. 120

3. In combination with a coin controlled 130

4
actuating mechanism, a fraud preventing device arranged above said mechanism, and comprising a coin receiving means, a spring pressed member cooperating with said coin receiving means to bend a slug inserted therein, and a deflector member operatively connected to said shaft and interposed between said aforementioned means and said coin controlled actuating mechanism to prevent the bent slug entering the mechanism.

5 10 15 20 25 30 35 40 45 50 55 60 65 70 75 80 85 90 95 100 105 110 115 120 125 130 135

4. A fraud preventing device for a coin controlled mechanism comprising a rotatable shaft provided with a coin receiving pocket, a spring pressed roller supported adjacent the pocket and cooperating with said shaft to bend a slug placed in the pocket when the shaft is rotated, a hopper arranged below the shaft, and a rotatable plate operatively connected to said shaft for guiding a mutilated slug into said hopper.

5 10 15 20 25 30 35 40 45 50 55 60 65 70 75 80 85 90 95 100 105 110 115 120 125 130 135

5. A fraud preventing device for a coin controlled mechanism comprising in combination, a rotatable shaft provided with a coin receiving pocket, a spring pressed roller supported adjacent said pocket and cooperating with the shaft to bend a slug placed in the pocket when the shaft is rotated, a hopper arranged below said shaft and adapted to deliver coins to the coin controlled mechanism, and means arranged above said hopper and operatively connected to said shaft for preventing a slug entering the hopper when discharged from the pocket in said shaft.

5 10 15 20 25 30 35 40 45 50 55 60 65 70 75 80 85 90 95 100 105 110 115 120 125 130 135

6. A fraud preventing device for a coin controlled mechanism comprising in combination, a rotatable shaft provided with a coin receiving pocket, a spring pressed roller supported adjacent said pocket and cooperating with the shaft to bend a slug placed in the pocket when the shaft is rotated, a hopper arranged below said shaft and adapted to deliver coins to the coin controlled mechanism, means arranged above said hopper for preventing a slug entering the hopper when discharged from the pocket in said shaft, said last mentioned means comprising a deflector member operably associated with the shaft to provide a closure for the hopper when in one position.

5 10 15 20 25 30 35 40 45 50 55 60 65 70 75 80 85 90 95 100 105 110 115 120 125 130 135

7. A fraud preventing device for a coin controlled mechanism comprising in combination, a rotatable shaft provided with a coin receiving pocket, a spring pressed roller supported adjacent said pocket and cooperating with the shaft to bend a slug placed in the pocket when the shaft is rotated, a hopper arranged below said shaft and adapted to deliver coins to the coin controlled mechanism, means arranged above said hopper for preventing a slug entering the hopper when discharged from the pocket in said shaft, said last mentioned means comprising a deflector member operably associated with the shaft to provide a closure for the hopper

when in one position, said deflector member further providing a guide chute for delivering a proper coin to said hopper when in another position.

8. A fraud preventing device for a coin controlled mechanism comprising in combination, a rotatable shaft provided with a coin receiving pocket, a spring pressed roller supported adjacent said pocket and cooperating with the shaft to bend a slug placed in the pocket when the shaft is rotated, a hopper disposed below the shaft and adapted to deliver coins to the coin controlled mechanism, an additional hopper arranged adjacent the aforementioned hopper, and means operatively connected to said shaft and arranged above the first mentioned hopper to prevent slugs entering the same when disposed in one position, said means when disposed in such position providing a guide to deliver the slugs to the additional hopper.

9. A fraud preventing device for a coin controlled mechanism comprising in combination, a rotatable shaft provided with a coin receiving pocket, a spring pressed roller supported adjacent said pocket and cooperating with the shaft to bend a slug placed in the pocket when the shaft is rotated, a hopper disposed below the shaft and adapted to deliver coins to the coin controlled mechanism, an additional hopper arranged adjacent the aforementioned hopper, means arranged above the first mentioned hopper to prevent slugs entering the same when disposed in one position, said means when disposed in such position providing a guide to deliver the slugs to the additional hopper, said means comprising a deflector plate operably associated with the shaft.

10. A fraud preventing device for a coin controlled mechanism comprising in combination, a frame, a rotatable shaft mounted therein, said shaft having a series of coin receiving pockets formed therein, a series of brackets pivotally supported at their lower ends in the frame adjacent said shaft, a knurled roller journaled for rotation in the upper portion of each of said pivoted brackets and disposed adjacent the respective coin receiving pockets, resilient means associated with the bracket for normally urging the rollers toward the shaft, said rollers cooperating with the shaft to bend slugs placed in the pockets when the shaft is rotated.

11. A fraud preventing device for a coin controlled mechanism comprising in combination, a rotatable shaft provided with a coin receiving pocket, a spring pressed roller supported adjacent the pocket and cooperating with the shaft to bend a slug placed in the pocket when the shaft is rotated, a hopper disposed below the shaft and adapted to deliver coins to said coin controlled mechanism, the rear side of said hopper be-

ing cut away, an additional hopper arranged adjacent the rear side of the aforementioned hopper and disposed below the same, coacting inclined lips formed on the rear side 5 of the first mentioned hopper and at the top in the front side of said last mentioned hopper respectively, and means operatively connected to said shaft and arranged above

the first mentioned hopper to prevent slugs entering the same when disposed in one position, said means when in such position providing a guide to deliver the slug to the aforementioned additional hopper. 10

In testimony whereof I affix my signature.

WILLIAM F. DONATHAN.
